UNITED STATES PATENT OFFICE.

BURT A. PETERSON, OF ROCKFORD, ILLINOIS, ASSIGNOR TO BARBER-COLMAN COMPANY, OF ROCKFORD, ILLINOIS, A CORPORATION OF ILLINOIS.

COMBINED YARN CLEARER AND TENSION DEVICE.

Application filed November 28, 1924. Serial No. 752,740.

The invention has general reference to yarn winding machinery, and the primary object thereof is to provide a device which is capable of serving as an effectual clearing 5 device and which at the same time serves to place upon the running thread a fixed amount of tension.

Other objects are to provide a construction for the device which is simple in character; which renders the device capable of being readily cleaned, and which will effect a breaking of the thread in the event a slab or other irremovable obstruction is encountered.

15 In the accompanying drawings Figure 1 is a side elevation taken from the right-hand side of Fig. 3.

Fig. 2 is a vertical sectional view taken in the plane of line 2—2 of Fig. 3.

20 Fig. 3 is a front elevation.

Fig. 4 is a fragmentary plan view of certain thread guiding means comprised in the device.

The device herein shown is adapted for 25 use in connection with a winder of the type disclosed in the Colman Patents No. 1,267,977 and No. 1,274,386, granted May 28, 1918, and August 6, 1918, respectively. It will be apparent, however, that the device is also 30 adapted for use with other forms of spoolers and winders.

35 My combined yarn tensioning and clearing device comprises, in the preferred form illustrated, a pair of plates 5 and 5' providing two opposed, smooth, curved surfaces 6 and 6' between which the running thread is arranged to pass. Said plates are respectively supported at their upper ends by a pair of shafts 7 and 7' arranged in parallel relation 40 and mounted in two upright supporting members 8 and 8' of a U-shaped frame 9. The plates are bent along one edge so as to partially encircle the shaft 7 and 7', the latter being preferably polygonal in shape, 45 and from said shafts the plates depend downwardly and toward each other with the surfaces 6 and 6' disposed in opposed relation at the lower edges of the plate. When used with a winder of the type shown 50 in the before-mentioned Colman patents the plates are arranged out of contact with each other, as indicated in Fig. 1.

The U-shaped frame 9 is mounted prefer-

ably upon a plate 10 having down-turned flanges 11 at front and rear edges and anchored to a suitable support 12 by means of two or more screws 13. A second plate 14 having upturned flanges 15 is entered between the base and the plate 10. The two plates are thus spaced apart vertically. The 55 frame 8 is secured to the plate 10 by means of a bolt 14a. An upturned flange 11a is formed on the left hand end of the plate 10 against which the frame is held by the bolt 14a.

60 Means is provided for guiding the thread in its passage upwardly between the clearing and tensioning plates 5 and 5'. This means consists of a shoulder 16 formed on a laterally extended end portion of the plate 10, 65 and a forwardly opening notch 17 in a laterally extended end portion of the plate 14. The notch is made of substantial depth and is a greater width at its forward end in order more readily to receive the thread. 70 The forward edge of the plate 10 is shaped to provide an outwardly and rearwardly inclined edge 18 for guiding the thread into the notch 17 in placing a thread in the device.

75 Between the upright members 8 and 8' of the frame 9 is inserted a generally U-shaped member 19 having an upwardly extending portion forming a spring clip 20 adapted to engage with a pair of rods 21 and 22 secured between the members 8 and 8' near the upper ends thereof. The rods 21 and 22 are located one above the other and engage with the clip 20 to hold the member 19 against turning. At the upper end of the 80 clip 20 it may be shaped as at 23 to receive and clamp the upper rod 21.

85 The rods 21 and 22 are extended laterally to the right as shown in Fig. 3 as is also a third rod 24 positioned directly below the rods 21 and 22. 25 are detector fingers co-acting with the rods 21, 22 and 24 which form a stationary grid between which and the detector fingers the thread passes.

90 The plates 5 and 5' are yieldingly held 100 with their lower curved ends 6 and 6' in the desired relation to each other by a pair of plates 26, one on each of the shafts 7 and 7', engaging the depending side portions 19a of the member 19 which thus constitute 105 leaf springs tending to rock the shafts 7

and 7' and thus move the surfaces 6 and 6' toward each other. To permit the shafts 7 and 7' to rock, all corners are sufficiently rounded, the apertures in the members 8 and 8' being circular in form.

Any suitable means may be employed to limit the movement of the plates 5 and 5' toward each other by the leaf springs 19. Herein I have shown for this purpose a finger 27, one end of which is mounted in an aperture in the upright frame member 8, large enough to permit of a rocking movement of the finger. The other end of the finger is slideable in a vertically disposed slot 28 in the upright frame member 8'. Between its ends the finger is flattened and provided with an aperture through which passes a bolt 29 anchored at its lower end in the base of the frame member 9. A coiled expansion spring 30 interposed between the frame member and the finger serves to hold the latter against the head of the bolt 29. By adjusting the bolt the position of the finger relative to the plates 5 and 5' may be readily determined, it being observed that the finger engages inclined surfaces 5^a on the plates above the curved surfaces 6 and 6'. Thus a nice adjustment of the distance between the surfaces 6 and 6' may be obtained, the distance varying in accordance with the amount of tension which it is desired to maintain on the thread, until the full force of the spring pressure is exerted against the plates and the thread. In any case a fixed amount of tension will be maintained upon the running thread by the frictional engagement of the thread with the surfaces 6 and 6'. Also, particles of extraneous matter on the thread will be cleared therefrom; and in the event that a relatively large and irremovable obstruction on the thread attempts to pass between the plates, a breakage of the thread will result because of the inertia of the parts combined with a substantial stiffness in the leaf springs 19^a which hold the plates against opening or separating when the obstruction is encountered.

To enable the device to be quickly and easily cleaned of matter accumulated between the plates 5 and 5', the shaft 7' is extended slightly beyond the left hand end of the U-shaped frame 9 and provided with a forwardly extending lever 31. This lever 55 may be operated manually, but is adapted to be operated mechanically as by a cam bar of the traveling mechanism shown in the Colman Patent No. 1,267,977.

To facilitate the placing of the thread 60 in the device and to insure that it shall not be obstructed in this operation by the forward plate 5, the latter is shortened at its right hand end as is shown clearly in Fig. 3 as is also the shaft 7. The curved guiding surface 18, it will be observed, projects

slightly beyond the plate 5 but terminates short of the end of the plate 5'. Thus in placing the thread in the device it is guided laterally and rearwardly by the surface 18 beyond the end of the plate 5, whence it 70 springs laterally to the left between the two plates as permitted by the guiding edge 16 (Fig. 4), the latter being disposed approximately in the vertical plane of the inner end of the notch or slot 17 in the lower plate 14, 75 and also in the plane of one side of the guide finger 24 above the plates 5 and 5'.

To permit of access to the screw 29 for purposes of adjustment, an aperture 32 is provided in the forward side of the member 19 (Fig. 2).

I claim as my invention:—

1. A combined yarn clearing and tensioning device having, in combination, a pair of parallel shafts located one in front of the other in laterally spaced relation, a pair of plates having their upper edges secured upon the respective shafts and depending therefrom and shaped to provide at their lower edges opposed curved surfaces, spring 90 means tending to move said plates toward each other, and a stop finger vertically adjustable between said plates and adapted to limit the movement of said curved surfaces toward each other by the action of said 95 spring means.

2. A combined yarn clearing and tensioning device comprising, in combination, a pair of plates shaped to provide oppositely curved smooth surfaces, means for supporting said plates with said surfaces in opposed relation, a member between said plates to limit the extent to which they may approach each other, and means for firmly holding said plates against said member to maintain a 100 fixed tension upon a thread passing between them.

3. A combined yarn clearing and tensioning device comprising, in combination, a pair of plates shaped to provide oppositely 110 curved smooth surfaces, means for supporting said plates with said surfaces in opposed relation, spring means for holding said plates in frictional engagement with a thread passing between them, and means for adjusting said plates relative to each other to provide a definite space between them and thus place the desired fixed amount of tension on the running thread.

4. A combined yarn clearing and tensioning device comprising a substantially U-shaped frame providing a pair of upright supporting members, a pair of rock shafts mounted in laterally spaced parallel relation in said upright members, leaf springs supported by said frame, a member rigid with each of said shafts and bearing against one of said leaf springs, and a pair of plates also rigid with said shafts and shaped to provide two opposed smooth surfaces be- 125 130

tween which the running thread may pass, the arrangement being such that said leaf springs operate upon said shafts whereby to hold said surfaces in frictional engagement with the thread.

5. A combined yarn clearing and tensioning device comprising a pair of rock shafts, a pair of plates carried by said shafts and providing two opposed smooth surfaces, 10 spring means acting to turn said shafts whereby to move said surfaces into frictional engagement with a thread passing therebetween, and adjusting means for varying the amount of tension placed upon the 15 thread by said plates, said adjusting means comprising a stop finger mounted for up and down movement between said

plates, and means for varying the position of said finger relative to the plates.

6. A device of the character described 20 comprising a pair of plates arranged in opposed relation and shaped to provide a pair of opposed thread guiding surfaces and a pair of surfaces inclined toward said thread guiding surfaces, spring means tending to move said thread guiding surfaces together, and a stop finger movable along said pair of inclined surfaces whereby to adjust the thread guiding surfaces relative to each other. 25

In testimony whereof, I have hereunto affixed my signature.

BURT A. PETERSON.
